UNITED STATES PATENT OFFICE.

WILLIAM C. HAKE, OF ST. LOUIS, MISSOURI.

RUBBING-OUT MACHINE.

Application filed June 27, 1922. Serial No. 571,326.

To all whom it may concern:

Be it known that I, WILLIAM C. HAKE, a citizen of the United States, and resident of St. Louis, Missouri, have invented an Improvement in Rubbing-Out Machines, of which the following description, in connection with the accompanying drawings, is a specification, like letters on the drawings representing like parts.

My present invention relates to shoe machinery and more particularly to a rubbing out machine utilized for laying down French binding so as to make such binding simple to fold.

Heretofore in the manufacture of shoes, one of the most difficult operations has been the putting on of French binding in a satisfactory manner. No machine of which I am aware is capable of properly performing this operation, and the cost of hand labor for doing the same is so great as to be prohibitive if such binding is to be used in moderate priced shoes. Heretofore, after the binding is stitched on to the vamp, it is necessary that the binding be laid out flat preparatory to folding the same either by hand or machine. As the laying out operation has heretofore been performed by hand, the expense has been such as to preclude the use of French binding on any but high priced shoes. With a view to performing the laying out or rubbing out operation by machine, and thus making it possible to use French binding on practically all classes of shoes, I have devised a machine forming the subject matter of the present invention. In carrying out my invention, I have arranged a plurality of rubbing or feeding wheels rotatably mounted on shafts at an angle to each other and through which the vamp to which the binding has been stitched, is fed, the wheels rotating and the surfaces thereof moving relatively to each other to cause a rubbing down or smoothing out action of the binding. In the preferred embodiment of my invention, one wheel may be called the feeding wheel and the other the rubbing wheel, and operating in conjunction with said wheels is a plurality of tension devices which act to maintain the wheels in close association with each other and to cause the positive feeding of the vamp through the machine.

The particular object of my invention is an improved rubbing out machine for rubbing out or laying flat the French binding

used on the vamps employed in the manufacture of shoes.

Another object of my invention is an improved combination of feeding and rubbing out wheels cooperating with spring tension devices for insuring smooth and positive feeding of the material through the machine. Other objects and novel features of the construction and arrangement of parts will appear as the description of the invention progresses.

In the accompanying drawings illustrating a preferred embodiment of my invention:

Fig. 1 is a side elevation;

Fig. 2 is a front end elevation;

Fig. 3 is a plan view;

Fig. 4 is an enlarged detail of the feeding wheels taken on the line 4—4 of Fig. 3;

Fig. 5 is a side elevation of the upper portion of the machine from the opposite side to the view shown in Fig. 1;

Fig. 6 is a vertical sectional elevation on the lines 6—6 of Fig. 1;

Fig. 7 is a vertical section on the lines 7—7 of Fig. 3, and

Fig. 8 is a section taken on the line 8—8 of Fig. 1.

Referring to the drawings, 10 designates a base or standard provided intermediate its upper and lower ends with a horizontal enlargement or extension 11 in which is rotatably mounted a shaft 12, this shaft 12 having secured thereto at one end a driving pulley 13 which may be connected by means of a belt with any convenient source of power. At the other end is secured a knurled or toothed feeding wheel 14 of suitable diameter. The upper end of the base 10 or standard 10 is grooved or slotted as shown at 15 in Fig. 6, and pivotally mounted in said slot by means of a bolt 16 are two plates 17 and 18. The forward end of the wheel 17 or the end remote from the driving wheel 13 extends to a point substantially over the feeding wheel 14 and is provided with a bearing (not shown) in which is rotatably mounted a horizontal shaft 19. Pivotally secured to the side of the base or standard 10 by a bolt 20 is a bearing plate 21 the forward end of which is provided with a bearing (not shown) in alignment with the bearing on the forward end of the member 17, this bearing having rotatably mounted therein the shaft 19. At one end of the shaft 19 is secured a knurled or corrugated rubbing

disc or wheel 22, one face of which lies in a vertical plane that lies at one side of a vertical plane passing through the axis of the shaft 12. At the other end of the shaft 12, 5 19 is secured a flanged pulley 23. Pivotally mounted on one side of the base or standard 10 on a bolt 24 is a bell crank lever to the end of one arm 25 of which is secured a spring 26, the end of the spring being 10 secured in any convenient manner to the base or standard 10, this spring tending to move the outer end of the other arm 27 of the bell crank lever upward as viewed in Fig. 1. This arm 27 is provided with a 15 slot 28 through which passes a screw 29 that screws into the side of the base or standard 10, the screw and slot cooperating to hold the bell crank lever in any desired adjusted position. At the extreme end of 20 the arm 27 of the bell crank lever is provided a bolt 30 on which is rotatably mounted a flanged pulley 31. Above the pulley 31 and on the base or standard 10 is a bolt 32 which makes an angle with the 25 horizontal, and on this bolt 32 is rotatably mounted a flanged wheel 33. On the shaft 12 and between the driving pulley 13 and the base or standard 10 is secured a flanged pulley 34, and over the pulleys 34, 31, 23 and 30 wheel 33 runs an endless belt 35, this belt transmitting power from the main shaft 12 to the shaft 19 and therefore to the rubbing wheel 22. The member 18 is provided with an elongated slot 36 which allows the member 35 to have considerable relative movement with respect to the shaft 19 and also with the member 17. The ends of the members 17 and 18, remote from the shaft 19, are perforated to receive any suitable means leading to a treadle or the like and by means of 40 which the said members may be rotated about the bolt 16 to raise or lower the rubbing wheel 22.

On the top of the base or standard 10, and 45 near the front thereof, is formed an upright portion 37 provided with threaded and countersunk holes in alignment with the members 17 and 18 (see Fig. 8), and in the countersunk portion are spring pressed flanges 38 actuated, each of them, by compression springs 39 and the tension of these springs is adjusted by means of the adjusting screws 40. The flanges 38 engaging 50 with the forward end of members 17 and 18 tend to force said forward end downwardly and hold the rubbing wheel 22 into close association with the feed wheel 14 under spring tension. The extreme front lower 55 end of the member 18 is provided with a pair of downwardly extending arms 41 at the lower end of which is secured a shaft 42 and on the shaft is rotatably mounted a 60 presser roller 43 which is spring pressed downwardly into engagement with an anvil 44 adjacent the feed wheel 14. Secured to

one side of the forward end of the extension 11 by screw 45 is an adjustable guide 46 arranged to limit the extent of inward movement of the material being operated upon. 70

The diameters of the flange pulley 34 and the rubbing wheel 22 are so proportioned with respect to the diameter of the feed wheel 14 that the peripheral speed of the wheels 22 and 14 is substantially equal. 75 While the feed wheel 14 cooperates with the roller 43 to cause a feeding action of the material transversely of the plane of rotation of the wheel 22, the wheel 22 acts in conjunction with the feed wheel 14 and 80 the roller 43 to feed the material through the machine and to smooth and lay down the French binding employed. To operate the device, the foot treadle (not shown) is operated to depress the left hand end of the 85 levers 17 and 18 (see Fig. 1) and thus raising the wheel 22 and roller 43 away from the feed wheel 14 and anvil 44 respectively and enabling the operator to slide the material to which the French binding has 90 been stitched, into position on the feed wheel 14. The treadle is now released and the springs 39 acting on the flanges 38 force the wheel 22 and roller 43 downward with a yielding tension, and the material being 95 worked upon is firmly held in position. On rotation of the shaft 12 from any suitable source of power, the wheels 22 and 14 are rotated in unison, causing a simultaneous 100 feeding of the material through the machine and a laying or rubbing down of the French binding.

While I have necessarily shown and described the preferred embodiment of my invention somewhat in detail, it is to be understood that I may alter the arrangement and size of parts shown, and constituting my improved machine, within wide limits without departing from the spirit of the invention. 105

Having thus described my invention, what I claim as new is:

1. In a rubbing out machine of the class described, the combination with a feed wheel arranged to rotate in a vertical plane and having a circumferential feed surface for feeding the work, of a rubbing wheel arranged to rotate in a vertical plane substantially at right angles to the plane of rotation of said feed wheel, whereby the circumferential surface of said rubbing wheel passes across the feeding surface of said feed wheel, and means for rotating said wheels in unison. 115

2. In a rubbing out machine of the class described, the combination with a feed wheel arranged to rotate in a vertical plane and having a circumferential feed surface for advancing the work, of a rubbing wheel above said feed wheel arranged to rotate in a vertical plane intersecting the plane of 120 130

rotation of said feed wheel, resilient means for actuating said rubbing wheel toward said feed wheel, and means for simultaneously rotating said wheels.

5. 3. In a rubbing out machine of the class described, the combination with a feed wheel arranged to rotate in a vertical plane and having a circumferential feed surface, of a rubbing wheel arranged to rotate in a vertical plane intersecting the plane of rotation of said feed wheel, a presser roller arranged to rotate in a plane parallel with said feed wheel, said roller being disposed at one side of the plane of rotation of said rubbing wheel, and means for rotating said feed wheel and said rubbing wheel at substantially the same peripheral speeds.
10. 4. In a rubbing out machine of the class described, the combination with a feed wheel arranged to rotate in a vertical plane and having a circumferential feed surface, of a rubbing wheel arranged to rotate in a vertical plane intersecting the plane of rotation of said feed wheel, a resilient support for said rubbing wheel, a presser roller arranged to rotate in a plane parallel with said feed wheel, said presser roller being disposed at the side of the plane of rotation of said rubbing wheel, a resilient support for said presser roller, and means for rotating said feed wheel and said rubbing wheel at substantially the same peripheral speeds.
15. 5. In a rubbing out machine of the class described, the combination with a feed wheel arranged to rotate in a vertical plane and having a circumferential feed surface, of a rubbing wheel arranged to rotate in a vertical plane intersecting the plane of rotation of said feed wheel, a resilient support for said rubbing wheel, a presser roller arranged to rotate in a plane parallel with said feed wheel, said presser roller being disposed at the side of the plane of rotation of said rubbing wheel, and means for rotating said feed wheel and said rubbing wheel at substantially the same peripheral speeds.

30. 35. 40. 45.

to rotate in a plane parallel with said feed wheel, said presser roller being disposed at the side of the plane of rotation of said rubbing wheel, and means for rotating said feed wheel and said rubbing wheel at substantially the same peripheral speeds.

5. In a rubbing out machine of the class described, the combination with a feed wheel arranged to rotate in a vertical plane and having a circumferential feed surface, of a rubbing wheel arranged to rotate in a vertical plane intersecting the plane of rotation of said wheel, a resilient support for said rubbing wheel, a presser roller arranged to rotate in a plane parallel with said feed wheel, said presser roller being disposed at the side of the plane of rotation of said rubbing wheel, a resilient support for said presser roller, and means for rotating said feed wheel and said rubbing wheel at substantially the same peripheral speeds.

In testimony whereof, I have signed my name to this specification.

WILLIAM C. HAKE.
